UNITED STATES PATENT OFFICE.

JOHN TRIX, OF DETROIT, MICHIGAN.

INJECTOR.

SPECIFICATION forming part of Letters Patent No. 632,481, dated September 5, 1899.

Application filed March 29, 1899. Serial No. 711,034. (Model.)

To all whom it may concern:

Be it known that I, JOHN TRIX, of Detroit, in the county of Wayne and State of Michigan, have invented a new and useful Improvement 5 in Injectors, of which the following is a specification.

My invention relates to injectors; and the object of my improvements is to provide an improved combined lifting and forcing injector and one which may be operated by the manipulation of a single stem or handle. I accomplish this object in the device illustrated in the accompanying drawings, in which—

15 Figure 1 is a vertical central section of an injector embodying my invention, showing by full lines the stem of the valves in the position in which the steam is entirely shut off and by dotted lines in the position for starting the lifting apparatus. Fig. 2 is a similar view showing by full lines the stem of the valves in operative position for the lifting apparatus and in position for starting the forcing apparatus and by dotted lines in operative 20 position for both the forcing and lifting apparatuses, and Fig. 3 is a horizontal section on the line X X of Fig. 1.

The same reference-letter indicates the same part in all the views.

30 A is the casing.

B is the inlet-port for the steam, and C that for the water.

D is the port through which the overflow is carried away, and E is the port or passage 35 through which the water is forced into the boiler.

F is the nozzle, and G the tube, of the lifting apparatus.

H is the nozzle, and I the tube, of the forcing apparatus.

J is a conical aperture formed in the casing A.

K is a conical plug adapted to fit closely into the aperture J.

45 L is a nut whose threads engage with the corresponding threads upon the casing A. The nut L acts to hold the plug K firmly in place in the casing. In the plug K are located the various valves and corresponding 50 ports and the stem by which said valves are operated.

M is a valve-stem in the plug K, its axis co-

inciding with that of said plug. M' are screw-threads upon the stem M, engaging with corresponding threads in the upper portion of 55 the plug K. The lower end of the plug K is united to the remainder thereof by screw-threads m, so that it may be detached to insert or withdraw the valve-stem and valves.

N P and Q R S are chambers in the plug K, 60 connecting, respectively, with the steam-port B, the lifting-nozzle F, the forcing-nozzle H, the forcing-tube I, and lifting-tube G, and with the overflow D.

T is a port connecting the chambers N and 65 P; U, a port connecting the chambers P and Q; V, a port connecting the chambers R and S, and W a port connecting the chamber S with a passage-way Y, which passage-way is open to the port E. 70

Z is a stuffing-box around the stem M where it comes out of the plug K, and a is a stuffing-box around said stem between the chambers Q and R.

p is an annular disk around the stem M, and 75 q is a gland forming in connection with the disk p the stuffing-box a.

b is a disk valve adapted to close the port T at its lower end.

d is a cylinder or piston-valve adapted to 80 fit closely in and pass through the port U. The cylinder d is fixed upon and concentric with the stem M. e is a similar cylinder or piston-valve adapted to fit closely in the port V.

f is a valve adapted to close the port W. 85

g is a cylindrical chamber in the casing A, communicating with the lifting-tube G and chamber R.

The passage-way D', communicating with the overflow-port D, passes around the chamber f and communicates with the chamber S. 90

The operation of the above-described device is as follows: Commencing with the stem M in the position shown in Fig. 1, in which the port T is closed, shutting off the steam, 95 so that no action can take place, the stem M is turned by means of the handle M², carrying said stem downward by means of the threads M' and lowering the valve b away from its seat. The parts are now in the position shown in dotted lines in Fig. 1. The steam is free to pass through the port T to the lifting-nozzle F; but the port U is still closed by the piston-valve d. The steam rushing

through the nozzle F and tube G creates a vacuum above said tube and draws the water up through the port C. The water passes through the lifting-tube G into the chamber g 5 to the chamber R through the port V into the chamber S, from whence it passes through the passage D' and out at the overflow-port D. When a strong solid stream is established through the lifting-tube G, the stem M is 10 again turned, carrying the parts down to the position shown in Fig. 2. Now the cylinder d has passed through the port U, so that steam is free to pass through said port to the forcing-nozzle H, and the cylinder e has passed 15 into the port V, thus closing said port and shutting off the connection between the lifting-tube G and the overflow. The water now passes through the lifting-tube G into the chamber g to the chamber R to the upper end 20 of the forcing-tube I, where it receives an additional impulse. It then passes through the forcing-tube I, through the passage Y and port W to the chamber S, from whence it passes through the passage D' and out through 25 the overflow-port D. When a strong solid stream has been established through the forcing-tube I, the stem M is again turned, bringing the parts into the position shown in dotted lines in Fig. 2, in which position the ports 30 T and U are wide open, leaving an unobstructed passage for the steam to the lifting and forcing nozzles F and H, and the ports V and W are closed, shutting off communication between the delivery ends of the lifting 35 and combining tubes G and I. The water will now be forced through the port or passage E to the boiler.

It will be noticed that the several operations will be accomplished by the manipulation 40 of the stem M and that the valves are readily accessible by removing the plug K from the casing A.

Having fully described my invention, what I claim, and desire to secure by Letters Patent, is—

1. In a combined lifting and forcing injector, the case, A, the conical aperture, J, therein, the conical plug, K, in said aperture, said plug being provided with chambers, N, P, Q, 50 communicating respectively with the steam-supply, the lifting-nozzle, and the forcing-nozzle, said plug being also provided with a chamber, R, communicating with the delivery end of the lifting-tube and the receiving 55 end of the forcing-tube, the various ports

and valves and valve-operating mechanism being located in said plug, substantially as shown and described.

2. In a combined lifting and forcing injector, the case, A, the conical aperture, J, therein, the conical plug, K, in said aperture, said plug being provided with chambers, N, P, Q, 60 communicating respectively with the steam-supply, the lifting-nozzle, and the forcing-nozzle, said plug being also provided with the chambers, R, and, S, the chamber, R, communicating with the delivery end of the lifting-tube, the receiving end of the forcing-tube, and with the chamber, S, and the chamber, S, communicating with the overflow and 70 with the delivery end of the forcing-tube, the various ports and valves and valve-operating mechanism being located in said plug, substantially as shown and described.

3. In an injector the case, A, the conical aperture J, in said case, the conical plug, K, in said aperture, a valve-stem, M, in said plug, said plug being provided with the various chambers substantially as described, and a stuffing-box, a, between two of said chambers 80 substantially as shown and described.

4. In an injector the case, A, the conical aperture, J, in said case, the conical plug, K, in said aperture, a valve-stem, M, in said plug, said plug being provided with the various 85 chambers, substantially as described, an annular disk, p, around said stem between two of said chambers, and a gland, q, forming a stuffing-box in connection with said annular disk, substantially as shown and de- 90 scribed.

5. In a combined forcing and lifting injector, the case, A, the conical aperture, J, therein, the conical plug, K, in said aperture, said plug being provided with chambers, N, P, Q, 95 communicating respectively with the steam-supply, the lifting-nozzle, and the forcing-nozzle, said plug being also provided with a chamber, R, communicating with the delivery end of the lifting-tube, and the receiving end 100 of the forcing-tube, the various ports and valves, and valve-stem being located in said plug, and a stuffing-box, a, located between the chambers, Q, and, R, substantially as shown and described.

JOHN TRIX.
